Primary Examiner—Sandra L. Morris**Attorney, Agent, or Firm**—Woodard, Naughton Moriarty & McNett**[57] CLAIM**

The ornamental design for a bird hand held toy, as shown and described.

DESCRIPTION

FIG. 1 is a front perspective of a bird hand held toy showing a first embodiment of my new design;

FIG. 2 is a right side elevational view thereof, the left side being substantially a mirror image;

FIG. 3 is a front elevational view thereof;

FIG. 4 is a top plan view thereof;

FIG. 5 is a rear elevational view thereof;

FIG. 6 is a bottom plan view thereof;

FIG. 7 is a front perspective of a bird hand held toy showing a second embodiment of my new design;

FIG. 8 is a right side elevational view thereof, the left side being substantially a mirror image;

FIG. 9 is a front elevational view thereof;

FIG. 10 is a top plan view thereof;

FIG. 11 is a rear elevational view thereof; and,

FIG. 12 is a bottom plan view thereof.
